J. H. HAMMOND, JR

SELECTIVE WAVE TRANSMISSION SYSTEM

Original Filed May 9, 1912

John Hays Hammond, Jr.
BY
A. J. Gardner
HIS ATTORNEY

UNITED STATES PATENT OFFICE.

JOHN HAYS HAMMOND, JR., OF GLOUCESTER, MASSACHUSETTS.

SELECTIVE-WAVE TRANSMISSION SYSTEM.

Original application filed May 9, 1912, Serial No. 696,113. Renewed December 19, 1919, Serial No. 346,169.
 Divided and this application filed October 29, 1920. Serial No. 420,439. Renewed March 15, 1924.

To all whom it may concern:

Be it known that I, JOHN HAYS HAMMOND, Jr., a citizen of the United States, residing at Gloucester, in the State of Massachusetts, have invented certain new and useful Improvements in Selective-Wave Transmission Systems, of which the following is a specification, this application being a division of my application Ser. No. 346,169, filed Dec. 19, 1919, in renewal of application, Serial No. 696,113, filed May 9, 1912.

My invention relates to improvements in systems for the transmission of energy by means of Hertzian or electro-radiant waves, and relates more particularly to systems wherein selectivity in transmission is secured by employing distinctive wave lengths and distinctive wave-group frequencies. In the system of this invention, I secure a still higher degree of selectivity by transmitting and receiving these waves and wave-groups at a third distinctive rate which may be obtained by means of interrupters, variations of wave amplitude or in other ways, as is hereinafter more fully set forth and described.

In the accompanying drawings:—

Figure 1 shows, in a diagrammatic form, a transmitting station containing a high-frequency alternator and two interrupters having different frequencies.

Figure 2 shows, in diagrammatic form, a receiving station having circuits responsive to three different frequencies of waves and wave groups.

Figure 3 shows, in diagrammatic form, a transmitting station having a medium-frequency alternator, a high-frequency alternator and an interrupter.

Figure 4 shows, in diagrammatic form, a transmitting station in which an electric arc is employed as the source of the electric oscillations.

Figure 5 shows, in diagrammatic form, a transmitting station having a high-frequency alternator, an interrupter and a motor-operated coil for varying the amplitude of the electric waves.

Figure 6 shows, in diagrammatic form, a transmitting station having a high-frequency alternator and an interrupter in one circuit and a medium-frequency alternator in another circuit, both circuits being in inductive relation to the antenna.

In Figure 1, the high-frequency alter-

nator H supplies energy to the coil L¹ through the interrupters I¹ and I² and the key K. The coil L¹ is in inductive relation with a coil L², which is connected with an antenna A, grounded at E, so that all the oscillations and wave variations occurring in coil L¹ will be impressed upon the antenna A and radiated therefrom.

The oscillation or wave frequency of the high-frequency alternator H may be, for example, 300,000 per second, corresponding to a wave length of about 1000 meters, the first interrupter I¹, which breaks these waves up into a primary series of groups, may have a frequency of 15,000 per second, and the second interrupter I², which divides these wave groups into a second series of groups or sets, may have a frequency of 750 per second. In the case assumed, each group or set of the second series will contain 20 groups of the first series, and each group of the first series will contain twenty waves. These waves and wave groups will then be radiated all together from the antenna.

This ratio of 20 to 1 between the frequencies of the waves and wave groups is merely cited as an example, and any other suitable ratio may be employed. Nor is it essential that the ratio between the wave frequency and the first group frequency be the same as that between the first group frequency and the second group frequency, but any suitable ratios to fit a particular case may be used. It is advisable that the first group frequency should be above the limits of audibility, so that a station attempting to interfere would have difficulty in determining its value, but this is not essential, except when the system in which the invention is embodied is used for radio telephony.

In Figure 2, the receiving antenna circuit B L³ C E⁵, consisting of the antenna B, the coil L³, the variable condenser C and the ground E⁵, is tuned to the wave frequency of the waves radiated from the transmitting station, and is coupled by means of the coils L³ and L⁴ with the oscillation circuit L⁴ C¹ containing the variable condenser C¹. The oscillation circuit L⁴ C¹ is also in tune with the wave frequency of the transmitting station. By means of the stopping condenser D and the rectifier R, the coil L⁵ receives unidirectional current from the circuit L⁴ C¹, these impulses having a frequency equal to that of the first series of wave groups.

of the transmitting station. The coil L^8 , being in inductive relation to coil L^6 , energizes the circuit, $L^6 C^2 L^7$, which contains the variable condenser C^2 and is in resonance with the said first group frequency of the transmitter. By means of the coupling coils L^7 and L^8 , oscillations are impressed upon the untuned circuit, $L^8 R^1 L^9$, and are converted by the rectifier R^1 into unidirectional impulses which have the same frequency as the second series of wave groups of the transmitter. The circuit, $L^{10} C^3 P$, which is inductively connected with coil L^9 , is in resonance with this second group frequency, and when the transmitting station is in operation the current impulses corresponding to the second group frequency will actuate the telephone receiver P and signals will be heard.

In Figure 3, G is an alternating current generator having a frequency of, for example, 7,500 cycles per second. The current from the generator G excites the field winding of the high-frequency alternator H^1 , and so impresses a series of amplitude variations on the current of the generator H^1 corresponding to a frequency of 15,000. The generator H^1 itself has a frequency in this case of 300,000 cycles per second, and delivers its current through the interrupter I^8 and the key K^1 to the coil L^{11} , and thence by means of the coupling coil L^{12} to the antenna A^1 which is preferably grounded as indicated at E^1 . If it is desired that the frequency of the series of amplitude variations should bear a ratio of 20 to 1 to the interrupter frequency, then the interrupter I^3 should have a frequency of 750 per second. In this arrangement of apparatus, the alternator G , by its periodic amplitude variation of the high-frequency current, produces the intermediate transmission frequency, and thus takes the place of the interrupter I^1 of Figure 1.

In Figure 4, an arc oscillatory current generator O is fed from a source of direct current $N N^1$. In a shunt circuit around the arc O are a condenser C^5 , an inductance coil L^{14} , an interrupter I^4 , and a key K^2 , and in another shunt circuit about the arc are a condenser C^4 and an inductance coil L^{18} . If the interrupter I^4 and the key K^2 are closed, then, as is well known in the art, when the parts O , C^5 and L^{14} are properly adjusted, oscillatory currents will be generated in circuit $O C^5 L^{14} I^4 K^2$, the frequency of which will be dependent upon the values of the condenser C^5 and coil L^{14} . Let this circuit be so adjusted that the frequency of these oscillations will be 300,000 per second. In a similar manner the circuit, $O C^4 L^{18}$, may be so adjusted that oscillations will be generated in it having a frequency of 7,500 cycles per second, and these oscillations will therefore produce a series of amplitude

variations in the current in circuit, $O C^5 L^{14} I^4 K^2$, having a frequency of 15,000 per second.

If the interrupter I^4 has a frequency of 750 per second, then there will be impressed upon the antenna A^2 , by means of the coupling coil L^{15} , electric oscillations having a frequency of 300,000 with amplitude variations of a frequency of 15,000, in groups having a frequency of 750 per second, and these waves and wave groups will be radiated from the antenna A^2 , which is preferably grounded as indicated at E^2 .

In Figure 5, H^2 is a high-frequency alternator supplying current to the antenna A^3 through the interrupter I^6 , key K^3 and coupling coils L^{16} and L^{17} . A motor M is mechanically connected to the coil L^{17} so as to rotate it in such a way as to produce a series of periodic amplitude variations, the frequency of which is preferably above the limit of audibility, in the current impressed upon the antenna A^3 . The frequency of the amplitude variations should be intermediate between the frequency of the alternator H^2 and the frequency of the interrupter I^6 . The antenna A^3 is grounded at E^3 .

In Figure 6, the high-frequency alternator H^3 induces oscillatory currents in the antenna A^4 through the interrupter I^6 , and key K^4 and the coupling coils L^{18} and L^{19} , and the alternator G^1 , with a frequency intermediate between the frequency of the alternator H^3 and the frequency of the interrupter I^6 , and preferably above the limits of audibility, impresses variations of amplitude upon the oscillatory currents in the antenna A^4 by means of the coupling coils L^{20} and L^{21} . The antenna A^4 is grounded at E^4 .

In the operation of the transmission system shown in Fig. 6, the alternator H^3 and its circuit including the interrupter I^6 and key K^4 causes the aerial circuit A^4 to emit a series of waves having a frequency determined by the alternator H^3 in a series of groups having an audible group frequency determined by the interrupter I^6 . The alternator G^1 acts upon this series of groups of waves in the aerial circuit $A^4 E^4$ produced by the alternator H^3 and its circuit to impress upon the waves periodic amplitude variations having a frequency in between the frequency of the alternator H^3 and the interrupter I^6 and preferably above audibility. The waves emitted by the aerial circuit are thus divided into a second series of groups having a frequency different from the first series of groups produced by the action of the interrupter I^6 .

In all these examples, the absolute frequencies and the relations between the frequencies may be of any values suitable for each case, and this invention is not limited to any particular frequencies. Nor is this

invention limited to the special apparatus here described, but any suitable means may be employed for producing the waves and wave groups or variations of wave amplitude transmitted, such, for example, as those described in my application for U. S. Letters Patent, Serial No. 693, 380, filed April 26th, 1912.

It is also evident that by adding one or 10 more interrupters of different frequencies to my apparatus, or by providing other suitable means for increasing the number of different frequencies of the wave groups, I may employ four or more different wave and wave- 15 group frequencies or variations of wave amplitude in one set, and so make my system additionally selective.

Having thus described my invention, what I claim and desire to secure by Letters Patent is:—

1. A signalling system comprising a transmission circuit, a circuit operatively connected to said transmission circuit including a source of periodic electrical im- 25 pulses of a predetermined frequency, and means for varying said impulses at a frequency different from said first mentioned frequency, a circuit operatively connected to said first mentioned circuit independently of 30 said second mentioned circuit and including means for producing periodic electrical impulses having a frequency different from either of said first mentioned frequencies, and means for receiving electrical impulses 35 produced in said first mentioned circuit through the operation of said other circuits, including two elements tuned to respond to said second and third mentioned frequencies, and a device arranged to be controlled by the conjoint action of said elements.

2. A signalling system comprising a transmission circuit, a circuit operatively connected to said transmission circuit includ- 45 ing a source of periodic electrical impulses of a predetermined frequency, and means for varying said impulses at a frequency different from said first mentioned frequency, a circuit operatively connected to 50 said first mentioned circuit independently of said second mentioned circuit and including means for producing periodic electrical impulses having a frequency different from either of said first mentioned frequencies,

and means for receiving electrical impulses 55 produced in said first mentioned circuit through the operation of said other circuits, including two elements tuned to respond to said second and third mentioned frequencies, and a device arranged to be controlled by the 60 conjoint and successive action of said elements.

3. A signalling system comprising a transmission circuit, a circuit inductively connected to said transmission circuit includ- 65 ing a source of periodic electrical impulses of a predetermined frequency, and means for varying said impulses at a frequency different from said first mentioned frequency, a circuit inductively connected to 70 said first mentioned circuit independently of said second mentioned circuit and including means for producing periodic electrical impulses having a frequency different from either of said first mentioned frequencies, and means for receiving electrical impulses produced in said first mentioned circuit through the operation of said other circuits, including two elements tuned to respond to 75 said second and third mentioned frequencies, and a device arranged to be controlled by the conjoint action of said elements.

4. A signalling system comprising a transmission circuit, a circuit inductively connected to said transmission circuit includ- 80 ing a source of periodic electrical impulses of a predetermined frequency, and means for varying said impulses at a frequency different from said first mentioned frequency, a circuit inductively connected to 85 said first mentioned circuit independently of said second mentioned circuit and including means for producing periodic electrical impulses having a frequency intermediate between said first mentioned frequencies, and means for receiving electrical impulses produced in said first mentioned circuit through the operation of said other circuits, includ- 90 ing two elements tuned to respond to said second and third mentioned frequencies, and a device arranged to be controlled by the conjoint and successive action of said elements.

Signed at New York, in the county of New York, and State of New York, this 105 23 day of October, A. D. 1920.

JOHN HAYS HAMMOND, JR.
